UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,935, dated November 28, 1893.

Application filed October 14, 1893. Serial No. 488,184. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of an arrangement of ornamental scrolls forming urn-shaped ornaments with a cornucopia-like ornament filled with flowers and leaves arranged in the center of said urn-shaped ornaments, and festoons of flowers and leaves hanging from the bottom of said ornamental scrolls and connected with the ornamental scrolls of the adjacent urn-shaped ornaments as represented 15 in the accompanying drawing. The border

or upper portion of the said design is also formed of ornamental scrolls with cornucopia-shaped ornaments filled with flowers and 20 leaves as shown, the ornamental scrolls being connected to form a continuous border.

What I claim is—

1. The design for wall paper herein shown and described.
2. In the design for wall paper, the border herein shown and described. 25

Witness my hand this 5th day of October, 1893.

CHARLES BOOZE.
